LASTING MACHINE

William Thomas Buckingham Roberts, Leicester,
England, assignor to United Shoe Machinery
Corporation, Flemington, N. J., a corporation of
New Jersey

Application February 23, 1943, Serial No. 476,828
In Great Britain February 28, 1942

25 Claims. (Cl. 12—14)

This invention relates to lasting machines, and in some aspects more particularly to machines for lasting the toe ends of shoes. The invention is herein illustrated as applied to a power-operated toe-lasting machine of the same general character as disclosed in United States Letters Patent No. 2,134,148, granted on October 25, 1938, on an application of mine, but modified in certain respects as further disclosed particularly in Letters Patent No. 2,138,308, granted on November 29, 1938, and No. 2,140,652, granted on December 20, 1938, also on applications of mine. It is to be understood, however, that the invention is not thus limited in its applicability.

A machine such as that to which the invention is herein shown as applied is provided with toe-embracing wipers which are operated to wipe the toe-end portion of an upper heightwise of a last, i. e., to perform what is commonly known as the upwiping operation, and are thereafter operated to wipe the margin of the upper inwardly over an insole on the last. Associated with the wipers is a device, hereinafter referred to as a retarder, which clamps the marginal portion of the upper outspread on the wipers about the end and along portions of the sides of the toe and cooperates with them to apply a pull to the upper in the upwiping operation, the retarder thereafter by its clamping action rendering the wipers more effective to wipe the margin of the upper tightly and smoothly inward over the insole. The retarder comprises a pair of upper-clamping fingers which are moved bodily lengthwise of the shoe with swinging movements also widthwise of the shoe to spread the margin of the upper from over the insole and are then moved heightwise of the shoe toward the wipers into positions to cooperate with them in the upwiping operation. Immediately after the upwiping movement of the wipers the shoe is moved a short distance heightwise in the opposite direction, after which the wipers are advanced and closed to wipe the margin of the upper inwardly over the insole. In time relation to such advancing and closing movements of the wipers the retarder fingers are moved farther outwardly over the wipers, releasing the margin of the upper. After the wipers have completed their advancing and closing movements, they are partially retracted from over the shoe bottom and are then moved inwardly again to positions short of the limits of their first inward movements, whereupon a plurality of fastening-inserting devices are operated to drive a row of tacks beyond the edges of the wipers to fasten the upper in lasted position.

Machines constructed as above briefly described

have been used with highly satisfactory results in operating on shoes of various styles and of different materials. In operating, however, on men's shoes having comparatively heavy uppers there is sometimes a tendency for looseness or wrinkling of the upper to develop at the sides of the toe near the tip line adjacent to portions of the upper which have already been lasted or at least pulled over and fastened to the insole, by reason of a tendency for the wipers to deflect portions of the upper near the tip line in a heelward direction as they are advanced and closed inwardly over the shoe bottom. An object of the present invention is to avoid such results in the toe-lasting operation. For the purposes in view, the construction herein shown comprises a pair of additional or auxiliary retarders arranged to clamp the margin of the upper on the wipers at the sides of the toe beyond the above-mentioned retarder fingers and controlled independently of the latter. The machine is provided with automatic means for moving the additional retarders widthwise of the shoe outwardly over the insole with a spreading action on the margin of the upper and for thereafter moving them farther outwardly over the wipers in time relation to the outward movements of the first-mentioned retarder fingers. As illustrated, however, the movements of the additional retarders are so timed that portions thereof still rest on the insole as the wipers approach them in the upwiping operation, so that they clamp the upper on the wipers only when the upwiping movement of the wipers has been substantially completed. The additional retarders are further so controlled that as they are moved outwardly over the insole they may be deflected in directions toward the end of the toe by engagement of portions of the margin of the upper therewith to avoid any substantial intervals between them and the ends of the first-mentioned retarder. In order that the additional retarders may be properly positioned relatively to the wipers and to the edge of the shoe bottom in operating on shoes of different widths, the invention further provides means for variably timing their outward movements, such means in the construction shown comprising a cam a portion of which is adjustable for the purpose in view.

The above and other features of the invention, including means for rendering the additional retarders inoperative at will, and various novel details of construction and combinations of parts, will now be more particularly described with reference to the accompanying drawings and thereafter pointed out in the claims.

In the drawings,

Fig. 1 is mainly a plan view of a portion of the machine in which the invention is herein shown as embodied, with the parts in their starting positions;

Fig. 2 is mainly a section on the line II—II of Fig. 1, with parts omitted;

Fig. 3 is a view in front elevation of certain parts shown in Fig. 1;

Fig. 4 is a plan view on an enlarged scale of certain parts shown in Fig. 1;

Fig. 5 is a section on the line V—V of Fig. 4;

Fig. 6 is a section on the line VI—VI of Fig. 4, with parts omitted;

Fig. 7 is a view substantially in front elevation of certain parts shown in Fig. 1;

Fig. 8 is a view in side elevation of a cam with which the machine is provided;

Fig. 9 is a section on the line IX—IX of Fig. 8;

Fig. 10 is mainly a plan view of the wipers and of parts associated therewith as they appear when the wipers are substantially at the end of their upwiping movement;

Fig. 11 is a view similar to Fig. 10, showing the same parts as they appear when the wipers have partially completed their movements to wipe the margin of the upper inwardly over the insole; and

Fig. 12 is a view partly in right-hand side elevation and partly in section, showing the wipers and other parts as they appear substantially at the beginning of the upwiping action of the wipers on the upper.

In view of the disclosures in the previously mentioned Letters Patent, only as much of the machine as it is necessary to refer to for an understanding of the invention is shown in the drawings and will be described in detail. For wiping the toe end of the upper heightwise of the last and for thereafter wiping its margin inwardly over an insole on the last the machine is provided with a pair of toe-embracing wipers 2 operated by means fully disclosed in the above-mentioned Letters Patent No. 2,134,148. The shoe is positioned bottom upward for the operation of the wipers thereon and is clamped and held in that position between an insole-engaging holdown 4 and a toe rest 6 (Fig. 12). Arranged to cooperate with the wipers is a retarder comprising two upper-clamping fingers 8 positioned initially over the toe end of the insole in contact therewith as illustrated by broken lines in Fig. 1. In the operation of the machine these fingers are moved lengthwise of the shoe toward the end of the toe and are also swung apart to insure the spreading of the margin of the toe end of the upper materials from over the insole, and as soon as they pass the edge of the insole they are moved downwardly toward the wipers so as to clamp the marginal portion of the upper outspread on the top of the wipers when the latter have been moved upwardly far enough to meet them, as illustrated in Fig. 12. As the wipers continue their upward movement to wipe the upper heightwise of the last the fingers 8 are lifted by the wipers while cooperating with them to apply a pull to the upper. After the upwiping movement of the wipers the shoe is forced downward a short distance by the holdown 4, and the wipers are then advanced and closed to wipe the marginal portion of the upper inwardly over the insole. In time relation to these movements of the wipers the fingers 8 are moved farther lengthwise of the shoe and are swung farther apart while still controlling the

margin of the upper until the latter is withdrawn from between them and the wipers by the movements of the wipers. Thereafter, following partial retractive movements and second inward movements of the wipers, a plurality of tackers 10 are moved into tack-inserting positions beyond the edges of the wipers and are then operated to drive tacks to fasten the toe end of the upper in fastened position. As thus far briefly outlined, the machine herein shown is intended to operate in substantially the same manner as heretofore.

For purposes of this invention the machine is provided with a pair of auxiliary retarders comprising upper-clamping fingers 12 arranged to control the margin of the upper at the sides of the toe in locations beyond the fingers 8 in a heelward direction. The fingers 12 are hook-shaped, as shown in Fig. 7, to render them more effective in spreading the margin of the upper outwardly from over the insole on which they rest initially, as illustrated in Fig. 1, in locations spaced considerable distances inwardly from the edge of the insole. These fingers are formed on the inner end portions of arms 14 which extend laterally of the shoe and, for a purpose herein-after explained, are pivotally mounted at their outer ends for swinging movements heightwise of the shoe on pins 16 supported on outwardly extending bars 18. A spring-pressed plunger 19 in each bar 18 tends to swing the arm 14 upwardly and holds it normally in a position determined by its engagement with the bar 18. Each bar 18 has formed therein a cam track 20 in which lies a roll 22 supported between the arms of a bifurcated member 24, these arms being far enough apart to permit limited swinging movement of the bar 18 axially of the roll 22 for a purpose herein-after described. Each member 24 has an upwardly extending stem 26 journaled in an arm 28 (Figs. 1 and 2) extending rearwardly from the upper end portion of a slide 30. This slide is vertically movable in guideways formed in a bracket 32 secured to and movable with the appropriate one of a pair of vertically movable slides 34 connected together by a transverse cross-head 36 which carries the previously mentioned holdown 4 (Fig. 12), the slides 34 and the cross-head 36 corresponding to the parts identified by the reference characters 69 and 67, respectively, in Letters Patent No. 2,134,148. A vertical screw 38 extends freely downward through a lug 40 on the bracket 32 and is threaded at its lower end in the lower end portion of the slide 30. A spring 42 through which the screw extends bears at its upper end against the lower face of the lug 40 and at its lower end against a shoulder on the slide 30 and thus serves to urge the slide in a downward direction, the downward movement of the slide being limited by engagement of the head of the screw 38 with the lug 40. The screw is held in a fixed position by means of a set screw 44 in the slide 30. The outer end portion of each of the bars 18 is bifurcated and carries a roll 46 mounted on a pin 48 in the bar. This roll rests on the upper surface of an arcuate guide rail 50 secured by bolts 52 to the rear end of a rearwardly extending arm 54 formed on the vertically movable slide 34 at that side of the machine. When, therefore, the two slides 34 are moved downwardly at a predetermined time in the operation of the machine to cause the holdown 4 to depress the shoe, the bars 18 are moved downwardly with the slides. Through the springs 42 the fingers 12 in their initial positions are held downwardly on

the insole when there is a shoe in the machine, and these springs are yieldable to permit upward swinging movements of the bars 18 in response to pressure of the upper on the lower faces of the fingers 12 when by the relative movements of the wipers and the shoe the wipers are caused to assume positions above the level of the insole preparatory to the wiping of the margin of the upper inwardly over the insole.

Mounted on each of the pins 48 is the lower bifurcated end of a member 56 provided with a stem 58 extending upwardly through the front end of a forwardly extending lever arm 60 mounted on a pin 62 for horizontal swinging movements. It will be noted that the front ends of the arms 60 are far enough above the lower bifurcated portions of the members 56 to afford leeway for vertical movements of the slides 34 and the bars 18 supported thereby. The left-hand lever arm 60 has integral therewith a rearwardly extending arm 64 connected by a link 66 to an arm 68 in fixed relation to the right-hand arm 60. Through parts including the link 66, therefore, the two arms 60 are coupled together, the arrangement being such that swinging movement imparted to the left-hand arm 60 in a clockwise direction to move the left-hand finger 12 outwardly over the insole will cause the right-hand arm 60 to swing in a counterclockwise direction and thereby to move the right-hand finger 12 also outwardly. For thus swinging the left-hand arm 60 the machine herein shown is provided with a cam track 10 (Fig. 1) formed in the periphery of a cam 72 fast on the left-hand end portion of a shaft 74 (Fig. 9), this shaft corresponding to that identified by the reference character 253 in Letters Patent No. 2,134,148. Lying in the cam track is a roll 76 mounted on a rearwardly extending lever arm 78 which is positioned below the cam 72 and is arranged to swing about a vertical stud 80 on the frame of the machine. Integral with the arm 78 is a forwardly extending arm 82 connected by means which will presently be described to the left-hand end of a link 84 which is connected at its right-hand end to a pin 86 positioned substantially midway between the opposite ends of the left-hand arm 60 for operating the latter.

The connections between the arm 82 and the link 84 are best shown in Figs. 4, 5 and 6. Mounted under the front end of the arm 82 to swing about pins 88 carried by the arm are two short arms 90 so formed as to extend part way around a boss 92 on the arm 82, this boss having therein an arcuate recess 94. Mounted between lugs extending from the arms 90 is a spring 96 which tends to swing the arms inwardly toward each other. Extending forwardly from the stud 80 is an arm 98 which is mounted to swing about the stud, and carried by this arm in a location substantially midway between its front and rear ends is a pin 100 movable vertically in a bore in the arm. Extending rearwardly from the pin 100 is a small pin 102 positioned in a slot 104 (Fig. 5) formed in a circular disk 106. This disk is fast on the rear end of a shaft 108 mounted to turn in the arm 98 and provided on its front end with a handle 110 for turning it. It will be evident that by turning the shaft 108 the pin 100 may be moved upwardly or downwardly. Normally the parts are so positioned that the pin 100 extends upwardly into the arcuate recess 94 of the boss 92 on the arm 82, and in this position it is also engaged by inwardly inclined shoulders 112 of the two arms 90. A tension spring 114 (Fig. 5) connected to a pin 116 on the disk 106 and to a pin

118 on the arm 98 serves by its action on the disk to hold the pin 100 in this position. At its front end portion the arm 98 is provided with a lug 120 connected to the left-hand end of the previously mentioned link 84.

From the foregoing description it will be understood that with the parts in their normal positions the cam-operated lever arm 82 is effective to operate the arm 98 through contact of its depending lug 92 and the arms 90 with the pin 100 carried by the arm 98. If it should be desired, however, not to use the auxiliary fingers 12, the operator by means of the handle 110 may move the pin 100 downwardly to free it from the lug 92 and the arms 90, after which the auxiliary fingers may be moved to out-of-the-way positions and the arm 82 will be moved idly during the power operation of the machine. If, moreover, the auxiliary fingers should strike against any part of the machine in returning to their initial positions after having operated on a shoe, no damage will result, since the pin 100 will wedge the arms 90 apart against the resistance of the spring 96 and the arm 82 will continue its movement without operating the arm 98.

The manner of operation of the machine, in so far as it is of interest with reference to the present invention, will now be briefly summarized. Shortly after the starting of the power operation of the machine, the shoe having been clamped between the holdown 4 and the toe rest 6, the main retarder fingers 8 are moved rearwardly over the insole toward the end of the toe and are also swung apart to insure that the margin of the upper will be spread from over the insole, the movements of these fingers continuing until they pass beyond the edge of the insole, whereupon they are moved downwardly a short distance, as illustrated in Fig. 12, into positions to clamp the marginal portion of the upper outspread on the top faces of the wipers 2 as soon as the wipers have been moved upwardly far enough to meet them. As the fingers 8 are thus moved outwardly over the insole, the auxiliary upper-clamping fingers 12 also begin to move outwardly with a spreading action on portions of the margin of the upper at the sides of the toe beyond the fingers 8. In their outward movements the fingers 12 may be deflected lengthwise of the shoe toward the fingers 8 by the action thereon of inwardly extending portions of the margin of the upper which are adjacent to portions already fastened, or at least pulled over and fastened to the insole, just beyond the toe portion of the shoe. In this manner the fingers 12 are maintained near the ends of the fingers 8, so that control of the margin of the upper will be substantially continuous all along the sides of the toe. It will be understood that such deflection of the fingers 12 lengthwise of the shoe is permitted by the provision for swinging movements of the bars 18 axially of the rolls 22, as hereinbefore described. Just before the wipers 2 complete their upwiping movement the inner end portions of the fingers 12 arrive in positions where they are over the edges of the wipers, as illustrated in Fig. 10, to render them effective to clamp the margin of the upper outspread on the wipers similarly to the fingers 8 near the end of the upwiping operation.

It will be understood that after the upper is first clamped on the wipers by the fingers 8, as shown in Fig. 12, further upward movement of the wipers serves to lift these fingers, the wipers

and the fingers cooperating to apply an upward pull to the upper in the upwiping operation. Immediately after the upward movement of the wipers the shoe is depressed a short distance by the holdown 4, thus causing the wipers and the fingers 8 to apply a further pull to the upper and positioning the shoe in proper relation to the wipers for the latter to wipe the marginal portion of the upper inwardly over the insole. As the shoe is thus moved downwardly the downward movements of the slides 34 which carry the holdown result in further compression of the springs 42 which control the bars 18 and the fingers 12, thus increasing the clamping pressure of the fingers on the margin of the upper over the wipers.

As the wipers are advanced and closed to wipe the upper inwardly over the insole the fingers 8 are moved farther rearwardly and are swung farther apart while clamping the margin of the upper on the wipers until the upper is withdrawn from under them by the wipers. At substantially the same time the auxiliary fingers 12 are moved farther outwardly while similarly controlling the margin of the upper at the sides of the toe beyond the fingers 8 (Fig. 11). In this manner the fingers 12 cooperate with the fingers 8 to counteract any tendency for the upper at the sides of the toe to be deflected in a heelward direction by the wipers in such manner as to cause any loosening or wrinkling of the upper in locations adjacent to the previously pulled-over or side-lasted portions. A machine such as that to which the invention is herein shown as applied comes automatically to a stop when the wipers are at the end of their overwiping movements to permit the operator to inspect the work, and when the machine is again started the wipers are partially retracted and are then moved short distances inwardly once more prior to the fastening of the upper in lasted position. In time relation to this second inward wipe the tackers 10 are moved into tack-inserting positions just beyond the edges of the wipers and are then operated to drive the tacks. After the second starting of the machine the auxiliary fingers 12 are moved still farther outwardly and by the action of the rolls 22 on the bars 18, by reason of the shape of the cam tracks 20, the fingers are swung upwardly away from the wipers to avoid interference with the latter in their further outward movements. In case any of the tackers in their downward and inward movements over the wipers toward tack-inserting positions should strike against the fingers 12 the latter may swing downwardly against the resistance of the spring-pressed plungers 19 to avoid any danger of damage to the machine. When the fingers 12 are moved inwardly to their starting positions after the operation of the machine on the shoe any danger of damage in case either of the fingers should strike against some part of the machine is avoided by the yieldable means provided for connecting the operating arm 82 to the arm 98, as hereinbefore explained.

To cause the auxiliary fingers 12 to cooperate properly with the wipers in the manner above described in operating on shoes of different widths, provision is afforded for variably timing the outward movements of the fingers over the shoe, so that they will arrive in positions over the edges of the wipers, as illustrated in Fig. 10, at substantially the same time relatively to the upwiping movement of the wipers in operating on a narrow shoe as in operating on a wide shoe. For

this purpose there is mounted on the shaft 74 (Fig. 9) for adjustment lengthwise of the shaft adjacent to the cam 72 a segmental member 188 which carries a hardened wear piece 190 arranged to serve as a portion of the left-hand wall of the cam track 70 by which the fingers 12 are operated. A pair of springs 192 mounted in the hub of the segmental member 188 tend by engagement with the hub of the cam to move the segmental member outwardly along the shaft. Threaded on the end of the shaft is a hand wheel 194, and fastened by bolts 196 to the inner side of this hand wheel is a hardened steel plate 198 arranged to bear on the hub of the segmental member 188. By turning the hand wheel, therefore, the position of the segmental member and of its wear piece 190 may be varied to vary the timing of the first portion of the outward movements of the fingers 12 as and for the purpose above described. Such an adjustment of the segmental member will be made when the wipers are changed preparatory to the use of the machine on shoes of a different size. In the steel plate 198 are a plurality of recesses 200 arranged to receive a spring-pressed detent 202 mounted in the hub of the member 188 to hold the hand wheel 194 in adjusted position.

Having described the invention, what I claim as new and desire to secure by Letters Patent of the United States is:

1. In a lasting machine, the combination with wipers movable to wipe the margin of the toe-end portion of an upper inwardly over an insole on a last, of a retarder for clamping the margin of the upper on said wipers around the end and along portions of the sides of the toe as it is thus wiped inwardly by the wipers, said retarder being movable lengthwise of the shoe outwardly over the wipers in the course of the wiping operation, additional retarders arranged to clamp the margin of the upper on the wipers at the sides of the toe beyond said first-named retarder, and means for controlling said additional retarders independently of the first-named retarder.
2. In a lasting machine, the combination with wipers movable to wipe the margin of the toe-end portion of an upper inwardly over an insole on a last, of a retarder for clamping the margin of the upper on said wipers around the end and along portions of the sides of the toe as it is thus wiped inwardly by the wipers, said retarder being movable lengthwise of the shoe outwardly over the wipers in the course of the wiping operation, additional retarders arranged to clamp the margin of the upper on the wipers at the sides of the toe beyond said first-named retarder, and means for moving said additional retarders outwardly over the wipers widthwise of the shoe in the course of the wiping operation.
3. In a lasting machine, the combination with wipers movable to wipe the margin of the toe-end portion of an upper inwardly over an insole on a last, of a retarder for clamping the margin of the upper on said wipers around the end and along portions of the sides of the toe as it is thus wiped inwardly by the wipers, said retarder comprising members movable bodily lengthwise of the shoe outwardly over the wipers with swinging movements also widthwise of the shoe in the course of the wiping operation, additional retarders arranged to clamp the margin of the upper on the wipers at the sides of the toe beyond said first-named retarder, and means for moving said additional retarders outwardly over the wipers widthwise of the shoe independently of the

first-named retarder in the course of the wiping operation.

4. In a lasting machine, the combination with wipers for wiping the toe-end portion of an upper into lasted position, of a retarder for clamping the margin of the upper on said wipers about the end of the toe to control the upper in the lasting operation, said retarder being movable to spread the margin of the upper from over the shoe bottom before clamping it on the wipers, additional retarders arranged to clamp the margin of the upper on the wipers at the sides of the toe beyond said first-named retarder, and means for moving said additional retarders widthwise of the shoe independently of said first-named retarder to spread the margin of the upper from over the shoe bottom in the course of the operation of the machine.

5. In a lasting machine, the combination with wipers for wiping the toe-end portion of an upper into lasted position, of retarder members for clamping the margin of the upper on said wipers at the end and along portions of the sides of the toe to control the upper in the lasting operation, said members being movable bodily lengthwise of the shoe with swinging movements also widthwise of the shoe to spread the margin of the upper outwardly, additional retarder members arranged to clamp the margin of the upper on the wipers at the sides of the toe beyond said first-named members, and means for moving said additional members widthwise of the shoe independently of said first-named members to spread the margin of the upper outwardly in the course of the operation of the machine.

6. In a lasting machine, the combination with wipers for wiping the toe-end portion of an upper into lasted position, of a retarder for clamping the margin of the upper on said wipers about the end of the toe to control the upper in the lasting operation, additional retarders arranged to clamp the margin of the upper on the wipers at the sides of the toe beyond said first-named retarder, bars arranged to extend widthwise of the shoe and supporting said additional retarders, and means for moving said bars lengthwise to impart to the additional retarders movements to spread the margin of the upper outwardly in the course of the operation of the machine.

7. In a lasting machine, the combination with wipers for wiping the toe-end portion of an upper into lasted position, of a retarder for clamping the margin of the upper on said wipers about the end of the toe to control the upper in the lasting operation, additional retarders arranged to clamp the margin of the upper on the wipers at the sides of the toe beyond said first-named retarder and movable widthwise of the shoe to spread the margin of the upper from over the shoe bottom in the course of the operation of the machine, and means supporting said additional retarders for movements lengthwise of the shoe toward said first-named retarder in response to deflecting action of the margin of the upper thereon.

8. In a lasting machine, the combination with wipers for wiping the toe-end portion of an upper into lasted position, of a retarder for clamping the margin of the upper on said wipers about the end of the toe to control the upper in the lasting operation, additional retarders arranged to clamp the margin of the upper on the wipers at the sides of the toe beyond said first-named retarder, bars arranged to extend widthwise of the shoe and supporting said additional retarders, and means for moving said bars lengthwise to impart

to the additional retarders movements to spread the margin of the upper from over the shoe bottom, said bars being supported for swinging movements to permit the additional retarders to be moved lengthwise of the shoe toward the end of the toe by deflecting action of the margin of the upper thereon.

9. In a lasting machine, the combination with wipers for wiping the toe-end portion of an upper into lasted position, of a retarder for clamping the margin of the upper on said wipers about the end of the toe to control the upper in the lasting operation, additional retarders arranged to clamp the margin of the upper on the wipers at the sides of the toe beyond said first-named retarder, bars arranged to extend widthwise of the shoe and supporting said additional retarders, means for moving said bars lengthwise to impart to the additional retarders movements to spread the margin of the upper outwardly, and spring means tending to swing said bars heightwise of the shoe to cause the additional retarders to press the margin of the upper on the wipers.

10. In a lasting machine, the combination with wipers for wiping the toe-end portion of an upper into lasted position, of a retarder for clamping the margin of the upper on said wipers about the end of the toe to control the upper in the lasting operation, additional retarders arranged to clamp the margin of the upper on the wipers at the sides of the toe beyond said first-named retarder, bars arranged to extend widthwise of the shoe and supporting said additional retarders, levers connected to said bars for moving them lengthwise to impart to the additional retarders movements to spread the margin of the upper outwardly in the course of the operation of the machine, means connecting said levers together, and a cam for operating both said levers.

11. In a lasting machine, the combination with wipers movable to wipe the toe-end portion of an upper into lasted position, of a retarder for clamping the margin of the upper on said wipers about the end of the toe to control the upper in the lasting operation, said retarder being movable lengthwise of the shoe outwardly toward the edge of the shoe bottom before clamping the upper on the wipers, additional retarders arranged to clamp the margin of the upper on the wipers at the sides of the toe beyond said first-named retarder, and power-operated means for moving said additional retarders widthwise of the shoe outwardly toward the side edges of the shoe bottom in adjustably predetermined time relation to the movements of the wipers.

12. In a lasting machine, the combination with wipers movable to wipe the toe-end portion of an upper into lasted position, of a retarder for clamping the margin of the upper on said wipers about the end of the toe to control the upper in the lasting operation, additional retarders arranged to clamp the margin of the upper on the wipers at the sides of the toe beyond said first-named retarder, and power-operated means including a cam for moving said additional retarders widthwise of the shoe outwardly toward the side edges of the shoe bottom in predetermined time relation to the movements of the wipers, a portion of said cam being adjustable to vary the timing of the movements of said additional retarders.

13. In a lasting machine, the combination with wipers movable to wipe an upper into lasted position at the opposite sides of a shoe, of retarders arranged to clamp the margin of the upper on

said wipers to control the upper in the lasting operation, and power-operated means including a rotatable cam common to both said retarders for moving them bodily widthwise of the shoe outwardly toward the side edges of the shoe bottom in predetermined time relation to the movements of the wipers, a portion of said cam being adjustable to vary the timing of the movements of the retarders.

14. In a lasting machine, the combination with means for wiping the margin of an upper into lasted position over an insole on a last, of a retarder for clamping the margin of the upper on said wiping means to control the upper in the lasting operation, said retarder being movable outwardly over the insole toward the edge of the shoe bottom prior to the clamping of the margin of the upper on the wiping means and having a hook-shaped portion for engaging the margin of the upper and spreading it from over the insole.

15. In a lasting machine, the combination with wipers for wiping the toe-end portion of an upper into lasted position, of a retarder for clamping the margin of the upper on said wipers about the end of the toe to control the upper in the lasting operation, and additional retarders arranged to clamp the margin of the upper on the wipers at the sides of the toe beyond said first-named retarder, said additional retarders being movable widthwise of the shoe outwardly toward the side edges of the shoe bottom and having hook-shaped portions for engaging the margin of the upper and spreading it from over the shoe bottom.

16. In a lasting machine, the combination with wipers for wiping the toe-end portion of an upper heightwise of a last and then inwardly over an insole on the last, of a retarder for clamping the upper on said wipers about the end of the toe as it is thus wiped heightwise of the last and inwardly over the insole, and additional retarders arranged to clamp the upper on the wipers at the sides of the toe beyond said first-named retarder only when the wiping of the upper heightwise of the last has been substantially completed.

17. In a lasting machine, the combination with wipers for wiping the toe-end portion of an upper heightwise of a last and then inwardly over an insole on the last, of a retarder for clamping the upper on said wipers about the end of the toe as it is thus wiped heightwise of the last and inwardly over the insole, and additional retarders for clamping the upper on the wipers at the sides of the toe beyond said first-named retarder, said additional retarders being arranged to rest on the insole in positions to clamp the upper on the wipers only when the wiping of the upper heightwise of the last has progressed far enough to render them effective thus to clamp the upper.

18. In a lasting machine, the combination with wipers movable to wipe the toe-end portion of an upper heightwise of a last and then inwardly over an insole on the last, of a retarder for clamping the upper on said wipers about the end of the toe as it is thus wiped heightwise of the last and inwardly over the insole, said retarder being movable heightwise of the last with the wipers, and additional retarders arranged to clamp the upper on the wipers at the sides of the toe beyond said first-named retarder only when the wipers have substantially completed their movement heightwise of the last.

19. In a lasting machine, the combination with wipers movable to wipe the toe-end portion of an upper heightwise of a last and then inwardly

over an insole on the last, of a retarder for clamping the upper on said wipers about the end of the toe as it is thus wiped heightwise of the last and inwardly over the insole, said retarder being movable heightwise of the last with the wipers, and additional retarders for clamping the upper on the wipers at the sides of the toe beyond said first-named retarder, said additional retarders being arranged to rest on the insole in positions to clamp the upper on the wipers only when the wipers have been moved far enough heightwise of the last to render them effective thus to clamp the upper.

20. In a lasting machine, the combination with wipers for wiping the toe-end portion of an upper heightwise of a last and then inwardly over an insole on the last, of a retarder for clamping the upper on said wipers about the end of the toe as it is thus wiped heightwise of the last and inwardly over the insole, said retarder being movable outwardly over the insole to a position beyond the edge thereof and then heightwise of the last toward the wipers into position for clamping the upper thereon, additional retarders arranged to clamp the upper on the wipers at the sides of the toe beyond said first-named retarder, and means for moving said additional retarders widthwise of the shoe outwardly over the insole to positions where portions only thereof are beyond the edge of the insole for clamping the upper on the wipers only when the wiping of the upper heightwise of the last has progressed far enough to render them effective thus to clamp the upper.

21. In a lasting machine, the combination with wipers for wiping the toe-end portion of an upper into lasted position, of a retarder for clamping the margin of the upper on said wipers about the end of the toe to control the upper in the lasting operation, and additional retarders arranged for optional use to clamp the margin of the upper on the wipers at the sides of the toe beyond said first-named retarder.

22. In a lasting machine, the combination with wipers for wiping the toe-end portion of an upper into lasted position, of a retarder for clamping the margin of the upper on said wipers about the end of the toe to control the upper in the lasting operation, additional retarders arranged to clamp the margin of the upper on the wipers at the sides of the toe beyond said first-named retarder, power-operated means for controlling said additional retarders in the course of the lasting operation, and means for preventing at the will of the operator such control of the additional retarders by said power-operated means to render them idle during the operation of the machine.

23. In a lasting machine, the combination with wipers for wiping the toe-end portion of an upper into lasted position, of a retarder for clamping the margin of the upper on said wipers about the end of the toe to control the upper in the lasting operation, and additional retarders for clamping the margin of the upper on the wipers at the sides of the toe beyond said first-named retarder, said additional retarders being arranged to be maintained at the will of the operator in idle positions to render them ineffective and thus to permit control of the upper by said first-named retarder alone.

24. In a lasting machine, the combination with wipers for wiping the toe-end portion of an upper into lasted position, of a retarder for clamping the margin of the upper on said wipers about the end of the toe to control the upper in the lasting operation, said retarder being movable to spread

the margin of the upper outwardly before clamping it on the wipers, additional retarders arranged to clamp the margin of the upper on the wipers at the sides of the toe beyond said first-named retarder, power-operated means for moving said additional retarders widthwise of the shoe independently of said first-named retarder also to spread the margin of the upper outwardly, and means for preventing at the will of the operator such movements of the additional retarders by said power-operated means to render them idle during the operation of the machine.

25. In a lasting machine, the combination with wipers for wiping the toe-end portion of an upper into lasted position, of a retarder for clamping the margin of the upper on said wipers about the 10 end of the toe to control the upper in the lasting

operation, said retarder being movable to spread the margin of the upper outwardly before clamping it on the wipers, additional retarders arranged to clamp the margin of the upper on the wipers at the sides of the toe beyond said first-named retarder, and power-operated means for moving said additional retarders widthwise of the shoe independently of said first-named retarder also to spread the margin of the upper outwardly, said power-operated means comprising parts arranged to be disconnected from each other to render the additional retarders idle and thus to permit said first-named retarder alone to be used during the operation of the machine.
